(57) **CLAIM**

The ornamental design for an information storage cartridge for electronic game machine, as shown and described.

DESCRIPTION

FIG. 1 is a front elevational view of an information storage cartridge for electronic game machine showing my new design;

FIG. 2 is a rear elevational view thereof;

FIG. 3 is a top plan view thereof;

FIG. 4 is a bottom plan view thereof; and,

FIG. 5 is a right side view thereof, a left side being a mirror image.
